JOHN D. IHLDER, OF NEW YORK, N. Y., ASSIGNOR TO OTIS ELEVATOR COMPANY, OF JERSEY CITY, NEW JERSEY, A CORPORATION OF NEW JERSEY.

ELEVATOR-DOOR LOCK.

1,159,586.

Specification of Letters Patent.

Patented Nov. 9, 1915.

Application filed April 10, 1912. Serial No. 689,754.

To all whom it may concern:

Be it known that I, JOHN D. IHLDER, a citizen of the United States, residing at New York, in the county of New York and State of New York, have invented a new and useful Improvement in Elevator-Door Locks, of which the following is a specification.

My invention relates to door locks, and although it may have a general application, it 10 is adapted to elevator doors, and more particularly to the doors of an automatic electric elevator.

One of the objects of my invention is to provide an improved, efficient and absolutely safe door lock in which it is impossible for one to receive an electric shock.

Another object of the invention is the provision of a lock which is positive in its action, both as to locking the door and the operation of circuit-closing mechanism co-acting with the locking and latching mechanism of the lock.

A further object of the invention is the provision of an improved lock for elevator doors having circuit closing devices whose function is effectually to prevent an elevator door from being unlocked or opened unless and until the elevator car has come to rest adjacent the corresponding floor landing, 25 said lock also preventing an elevator car from being moved away from a floor landing while any one of the several landing doors is either unlocked, unlatched or in open position.

Other objects of my invention will appear hereinafter, the novel combinations of elements being pointed out in the appended claims.

In the accompanying drawings, Figure 1 40 represents in part sectional elevation an elevator door lock containing an embodiment of my invention with the parts in locking and unlocking positions; Fig. 2 is a side view of the left hand part of the lock or lock casing of Fig. 1, looking in the direction of the arrows, *b*—*b*; Fig. 3 is a side view of the keeper casing or right hand part of the lock of Fig. 1, looking in the direction of the ar-

rows *a*—*a*; Fig. 4 shows the application of my invention to an elevator door; Fig. 5 is a 50 plan view of the contact device on top of the door; Fig. 6 is a fragmentary elevation view of the top of the door and adjacent casing showing the co-acting door contacts.

Like reference characters denote similar 55 parts throughout the various figures.

My improved lock contains one feature which is common to nearly all elevator door locks, and this feature is in having a controlling circuit of the elevator carried through 60 the electrical contacts of the lock, so that unless all of the parts of the lock are in proper position the elevator car cannot be operated, as its controlling circuit will be interrupted.

Referring to the drawings, 1 designates a lock casing which contains a sliding latch member 2 having upon its right hand end a latch tongue 3 adapted to co-act with a rectangular slot 34 in the casing 35. The casing 1 is carried upon a swinging elevator door while the casing 35 is secured to the door casing adjacent thereto. The latch member 2 is provided with a hand hold 4, access to which is obtained by means of a 75 hole 5 in the lock casing, whereby a person may insert one or more fingers and slide the latch in a left hand direction to unlatch the door, providing the latch is unlocked. Springs such as 7, 7, engage projections 6, 6, 80 upon the latch member and tend to move the latter into latching position, as shown on the drawing, its outward movement being limited by a shoulder 33. A lock member 24 is pivoted to the casing 1 by a pin 25, and 85 has a locking tongue 26 adapted to engage a notch 27 in the latch, in which position it prevents the latter from being moved to unlocking position. The lock 24 tends to move under the action of gravity out of locking 90 position, and this tendency is supplemented by a small compression spring 29 which bears against the lock and a stop 30 formed in the casing 1. The lock is moved to locking position by means of a lever 39 which is 95 pivoted at 40 to an offset support or bracket

41 formed integral with the keeper casing 35. A stout coil spring 42 urges the upper end of the lever 39 against a push rod 36, which in turn operates against the face 31 of the locking lever 24. The push rod 36 is adapted to slide freely through bosses formed in the casing 35 while a spring 37 surrounds the push rod and bears against a collar 38 affixed thereto and tending to move 10 this rod away from the lock member 24. It will be noted that the coil spring 42 is of sufficient power to overcome the action of the springs 37 and 29, so that, as long as the spring 42 is free to operate the lever 39, the 15 lock member 24 will be moved into a position to lock the latch against any movement, intentional or otherwise.

The latch 3 contains a cutaway portion in which is embedded a conductor 11 of copper 20 or other suitable conducting material, the same however being insulated on all sides from the metal of the latch by means of suitable insulation 12 such as fiber or mica, but exposed on its right hand end. A sliding pin 13 passes through the conductor 11 at right angles thereto, and while the same is always in electrical contact therewith, it is insulated from the latch 3. This pin is guided in fiber bushings 14, 14, which are 25 secured against movement in the latch. A collar 16 is secured to the sliding pin and a spring 15 bears against said collar and the conductor 11. The pin 13 is operated against the action of the spring 15 by the 30 lock lever 24, a piece of insulating material 28 being affixed to the locking lever in alignment with the said pin, so that the pin can never come into electrical contact with the said lever. A contact 17 co-acts with the 35 pin 13 and is supported in a bracket 18 carried upon an insulated base 21 secured to the casing 1. The contact 17 has a sliding movement in the bracket 18, limited by a collar 19 secured thereon which is acted 40 upon by a spring 20. The casing 35 contains a sliding contact 46 which is arranged in alignment with the latch conductor 11 and is carried by a bracket 47 secured to an insulated base 48 fastened to the casing 35, 45 and is spring pressed in a manner similar to the contact 17.

As before pointed out the locking lever 24 is normally maintained in locking engagement with the latch member by means of the 50 coil spring 42 acting through the lever 39 and push rod 36. When the elevator car stops at a landing, a movable cam 49 carried upon the car is projected outwardly so as to engage a roller 43 carried upon a rod 60 44 secured to the lever 39 by means of a set screw 45. This cam positively moves the lever into a position shown in broken lines in Fig. 1, thereby permitting the spring 37 to move the push rod 36 away from the

locking lever 24 and allowing the latter to 65 be moved out of locking engagement with the latch 2 by reason of the spring 29.

The cam 49 carried by the elevator car is similar to that shown and described in Patent No. 740,154 to Magnuson and Eskilsson, 70 granted September 29, 1903, and the same is preferably operated by means of a rotary electric motor such as shown and described in Patent No. 964,891, to Westlin, granted 75 July 19, 1910.

While the lever 39 may be operated by a fixed cam carried upon the car, I prefer to use a motor actuated or retracting cam, since the latter is only moved into operating position when the car is stopped at a floor 80 landing thereby preventing the momentary unlocking of a door as the elevator car passes a floor landing. This motor operated cam and the manner in which it co-operates with the door locking apparatus is illustrated in Fig. 4 in which an elevator car 69 shown in broken lines is suspended by one or more cables 50 and connected thereby to any suitable hoisting apparatus. A rotary motor 51, mounted preferably on top of the 90 car, is connected by a strap or rod 52 to the cam 49 which is in turn connected to the support 53 by means of the links 54 and 55. When the door 56 is closed, as indicated in Fig. 4, and the car and cam carried thereby 95 stop opposite said door, the motor may be de-energized so as to allow the cam 49 to move against the lower end of the lever arm 39, thereby permitting the locking lever to move out of locking position with the latch, 100 as already described.

Each elevator door is provided with a door lock similar to that shown in the drawings and the electrical contacts of each door lock are connected up in series by the conductors such as 57 and 58 which pass through insulating bushings 22 and 23 respectively in the lock casing. These conductors form a continuous unbroken circuit when the electrical contacts of all of the 110 door locks are in closed position. This series circuit is a part of the controlling circuit of the elevator car, hence it follows that if any one of the electrical contacts of the several door locks is in open-circuit position, 115 the controlling circuit is broken and the car cannot be operated in either direction. When a door is closed and locked its lock will assume the position shown in full lines in Fig. 1 and the electrical circuit through 120 the lock may be traced from the conductor 57, through the pin 46, conductor 11, pin 13, contact 17, to the outgoing conductor 58.

It will be observed that in order to complete a circuit through the lock, the latch 125 11 must be in its outward position and must also be in electrical engagement with the pin 46. In order to meet these conditions it is

essential that the door be closed and the latch 11 be housed in the rectangular opening 34 (see Fig. 3) of the casing 35. Furthermore, in addition to the above conditions, it is absolutely necessary to have the contact pin 13 in electrical engagement with the co-acting contact 17, and in order to fulfil this condition, the latch 3 must not only be in outward position in which the pin 13

10 registers or falls into alignment with the contact 17, but also the lock lever 24 must be in locking position with its tongue 26 firmly seated in the notch 27 of the latching member, otherwise the pin 13 would not be raised

15 into electrical contact with the contact 17.

It is readily seen that when the lock is in locked position, it becomes impossible for one to unlock the door by manual means or by the use of a tool, since the locking lever 24 is not accessible from the floor landing, hence cannot be moved except at the proper time and by the proper means such as the elevator car itself, and any attempt to withdraw the latch 3 by means of the hand hold 4 or otherwise, will be of no avail. Furthermore, the contacts 13 and 17 are not closed until after the member 24 has engaged with and securely locked the latch 3 in locking position, as shown. Since the operating circuit cannot be completed unless and until the contacts 13 and 17 are in electrical engagement with each other, it follows that the car cannot be started until after the door is closed and latched, and the latch securely locked against movement. Among the advantages resulting from this operation, it may be mentioned that the latch cannot be withdrawn unless the locking member 24 first be retracted, and this can only be done

40 when the car is stopped adjacent the corresponding floor landing. Then again, the operator cannot start the car while the door is opened, or while the door is unlocked even though the door be in closed position.

45 Hence all possibilities of accident to a passenger at a floor landing are absolutely done away with. Furthermore, the contact or conductor 11 is always dead when the door is opened, since, at such time the locking

50 member 24 is moved into dotted line position and the contact 13 is out of electrical engagement with the live contact 17. Thus it becomes impossible for one to receive an electric shock by coming in contact with the exposed conductor 11 either intentionally or by accident.

When the car is stopped at a floor landing, the cam 49 in the car is automatically moved into a position shown in broken lines in Fig. 1, and the door lock at the corresponding floor is permitted to assume the position shown by broken lines in this figure. As the cam swings the lever 39 out of mechanical contact with the push rod 36,

the latter will be moved outwardly by its spring 37 and away from the face 31 of the locking lever 24. The latter is now swung about the pivot 25 by the spring 29, and the pin 13 at once moves away from its co-acting contact 17, thereby interrupting the operating circuit of the elevator at this contact. The latch, now being unlocked, may be withdrawn by the hand hold 4 from engagement with the coacting slot 34 in the casing 35, and the door may be opened. Upon withdrawing the latch, the operating circuit is further interrupted as the latch conductor 11 moves away from the pin 46, thus introducing an additional safeguard against maintaining the operating circuit closed as the door is unlocked and unlatched. It will be observed that the conductor 11 is dead or deenergized when the door is opened, since the electrical connection is broken at the contact 17, and as an additional safeguard against any possibility of having this exposed conductor 11 energized, I have devised the arrangement illustrated in Figs. 5 and 6. Referring to these figures it will be seen that the conductor or wire 58 is led through the body of the door to a spring pressed contact 59 preferably arranged upon the top of the door out of reach of a person standing at the floor landing or in the car. A co-acting contact 60 is mounted in the upper door casing and slightly countersunk therein and arranged to register, or make contact with the contact 59, only when the door is in closed position. An arc-shaped guard plate 61, is secured to the door in such a position that when the door is opened this guard plate moves under the contact 60 and prevents any access thereto either intentional or accidental. When the door is closed, this guard plate is swung out of the way, permitting the contacts 59 and 60 to touch each other.

It will be noted that a lock embodying my invention involves a plurality of conditions of operation each and all of which must be met absolutely before the elevator system will be in condition for operation. The lock cannot be tampered with by unauthorized persons and may truthfully be considered absolutely "fool-proof". The various moving parts are actuated by substantial coil springs which are far more reliable and durable than the springs usually employed in door locks.

The lock is simple in construction and inexpensive to manufacture; requires no attention to keep it in working order, and all of the parts are generous in size and not likely to become impaired or broken in service.

While I have illustrated a lock which is arranged particularly for hinged or swinging doors, it is obvious that with slight changes in unimportant details the same

could readily be modified so as to operate on sliding or other doors, therefore I desire not to be limited to the precise construction and arrangement of parts herein disclosed, since it is obvious that one skilled in the art to which my invention pertains could readily make such changes without departing from the spirit and scope of my invention.

What I claim, and desire to have protected by Letters Patent of the United States is:—

1. In an elevator door lock, the combination of a lock casing, a keeper casing, a spring pressed latch in said lock casing, a pivoted locking member in said casing, a spring tending to move said locking member out of locking engagement with said latch, a circuit closing member controlled by said locking member, and an outside lever adapted to move said locking member into locking position.

2. In an elevator door lock, the combination of a lock casing, a keeper casing, a spring pressed latch in said lock casing, a pivoted locking member in said casing, a spring tending to move said locking member out of locking engagement with said latch, a circuit closing member controlled by said locking member, and an outside lever adapted positively to move said locking member into locking position.

3. In an elevator door lock, the combination of a spring pressed sliding latch, a locking member for locking said latch in locked position, a circuit controlling device operated by said locking member, and means controlled by the passage of an elevator car for effecting the release of said locking member to permit the said latch to be withdrawn.

4. In an elevator door lock, the combination of a spring pressed sliding latch, a locking member for locking said latch in locked position, a circuit controlling device operated by said locking member, and cam mechanism outside of said lock for effecting the release of said locking member to permit the said latch to be withdrawn.

5. In an elevator door lock, the combination of a sliding latch, a locking member for said latch, electrical contacts controlled by said latch and said locking member, arranged in such manner that an electric circuit may be completed from one contact device to the other only when said latch is locked in latching position.

6. In an elevator door lock, the combination of a sliding latch, a conductor associated with said latch, a contact device co-acting with said conductor, a locking member for locking said latch in locked position, and a contact device controlled by said locking member movable into circuit closing position only when said locking member is in locked position whereby a circuit may be

completed from one contact device to the other contact device only when the said latch is in latched and locked position.

7. In an elevator door lock, the combination of a sliding latch, an electric conductor carried by said latch and adapted to engage a contact device when said latch is in latching position, an additional contact device co-acting with said conductor, and a locking member arranged simultaneously to effect an electrical connection between said conductor and said additional contact device, and to lock said latch in latched position.

8. In an elevator door lock, the combination of a lock casing carried by the door, a keeper casing carried by the door casing, a latch in said lock casing, an electric conductor carried by said latch, a contact in said keeper casing co-acting with said conductor when the door is in latched position, a locking member for locking said latch in latched position, and a contact device co-acting with said conductor and controlled by said locking member, whereby a circuit may be closed between both of said contact devices only when said latch is locked in latching position.

9. In an elevator door lock, the combination of a lock casing, a keeper casing, a spring pressed latch in said lock casing, a pivoted locking member in said lock casing, an electrical contact controlled thereby, a spring tending to move said locking member out of locking engagement with said latch, and means adapted to move said locking member into locking position.

10. In an elevator door lock, the combination of a lock casing, a keeper casing, a spring pressed latch in said lock casing, a pivoted locking member in said lock casing, an electrical contact controlled thereby, a spring tending to move said locking member out of locking engagement with said latch, and spring operated means adapted to move said locking member into locking position.

11. In an elevator door lock, the combination of a lock casing, a keeper casing, a spring pressed latch in said lock casing, a pivoted locking member in said lock casing, an electrical contact controlled thereby, a spring tending to move said locking member out of locking engagement with said latch, and means for moving said locking member into locking position, said means being controlled by an elevator car to allow the locking member to be moved out of locking engagement with said latch.

12. In an elevator door lock, the combination of a lock casing, a keeper casing, a spring pressed latch in said lock casing, a pivoted locking member in said lock casing, an electrical contact controlled thereby, a spring tending to move said locking member

out of locking engagement with said latch, and spring pressed means for moving said locking member into locking position, said spring pressed means being controlled by
5 an elevator car to allow the locking member to be moved out of locking engagement with the said latch.

In testimony whereof, I have signed my name to this specification in the presence of two subscribing witnesses.

JOHN D. IHLDER.
